(57) **CLAIM**

The ornamental design for a rear bumper valance for a vehicle, as shown and described.

DESCRIPTION

FIG. 1 is a right, front perspective view of a rear bumper valance for a vehicle showing my new design; FIG. 2 is a left, front perspective view thereof; FIG. 3 is a left, rear perspective view thereof; FIG. 4 is a right, rear perspective view thereof; FIG. 5 is a front elevational view thereof; FIG. 6 is a rear elevational view thereof; FIG. 7 is a left side elevational view thereof; FIG. 8 is a right side elevational view thereof; FIG. 9 is a top plan view thereof; FIG. 10 is a bottom plan view thereof; and, FIG. 11 is another front elevational view thereof shown on a vehicle.

The portions of the vehicle shown in the FIG. 11 drawing view in a de-emphasized and half-tone form outside the broken lines and the broken lines representing the boundary and configuration of what is claimed as the design are all for environmental and illustrative purposes only and form no part of the claimed design.
